(57) **CLAIM**

The ornamental design for a main tool and T-square for scrapbooking work surface, as shown and described.

DESCRIPTION

FIG. 1 is a perspective view of a main tool and T-square together with a scrapbooking work surface showing the new ornamental design, the portions shown in broken lines forming no part of the design sought to be patented;

FIG. 2 is a perspective view of the T-square, the portions shown in broken lines forming no part of the design sought to be patented;

FIG. 3 is a top view thereof, the portions shown in broken lines forming no part of the design sought to be patented;

FIG. 4 is a left view thereof, and the portions shown in broken lines forming no part of the design sought to be patented;

FIG. 5 is a right view thereof, and the portions shown in broken lines forming no part of the design sought to be patented;

FIG. 6 is a front view thereof, and the portions shown in broken lines forming no part of the design sought to be patented;

FIG. 7 is a bottom view thereof, and the portions shown in broken lines forming no part of the design sought to be patented;

FIG. 8 is a back view thereof, and the portions shown in broken lines forming no part of the design sought to be patented;

FIG. 9 is a perspective view of the main tool, the portions shown in broken lines forming no part of the design sought to be patented;

FIG. 10 is a top view thereof, the portions shown in broken lines forming no part of the design sought to be patented;

FIG. 11 is a back view thereof, the portions shown in broken lines forming no part of the design sought to be patented;

FIG. 12 is front view thereof, the portions shown in broken lines forming no part of the design sought to be patented;

FIG. 13 is a right view thereof, the portions shown in broken lines forming no part of the design sought to be patented;

FIG. 14 is a left view thereof, the portions shown in broken lines forming no part of the design sought to be patented; and,

FIG. 15 is a bottom view thereof, the portions shown in broken lines forming no part of the design sought to be patented.
